Stephen A. Williamson
Secteur Patent

The Schedule referred to in this Letter Patent and making part of the same containing a description in the words of the said Stephen A. Williamson of his machine for Manufacturing Beavers' Heads or Knaps.

This machine has three principle powers or motions derived from one main shaft, two of which, two other additional powers or motions all of which execute the following parts in regular succession, viz, sawing, planing, cutting, gauging and rounding the Stone, Bladell, or Knaps, which is done by one rotation of the main shaft. The main shaft has three arms placed upon it, two of which are wheels one third of whose circumference are set with cogs, the other is a conical wheel or wedge which operates upon a lever that throws the flier forward which cuts the split and proper and conveys it to its proper place until round by the flier receiving a circular motion from one of the wheels on the main shaft. The flier is an instrument the bowels or levers of which are extended sufficiently to admit of a bearpit fitter with a yew, within its circumference it has a shaft extending from each end in a line with the centre of sufficient magnitude to admit of a hole through the centre on a line from end to end of sufficient size to give passage to the rib, which it winds on to admit of wheels on the body by which it is governed and bearings by which it is held to its proper place in the machine. the foot of the flier is the end and part which carries, cuts and proper the split and winds it firmly to its station, the foot of the flier has a passage nearly the length of its body, entering on the outside and coming parallel with the main passage of the ribs and coming out at the point through which the yew discharges itself upon the ribs, the point of the flier onto the split by being passed forward on the ribs past the throat or passage of the split to the ribs in a piece of metal made to fit the circumference of the flier. the same motion proper the split to

its proper place between the ribs so the same instant the flier takes circular motion and lays the yarn round the body of the ribs and commences the split. 2nd Division of plies. In turning the main shaft the first cog immediately engages the feeding apparatus and withdraws so the flier and conducts it to its place at the same instant the beam or swage on the main shaft is brought to bear upon the lever which holds the flier ahead until the flier and passes it to its proper station between the ribs and continues to hold the flier in this position until the second cog on the main shaft engages with other machinery which conveys motion to the flier and carriage at the same instant the beam by passing the yarn round the ribs which are placed on a regular degree by the carriage which governs them after which the fliers are forced back by a spring, which gives exception to a succeeding flier.

Application of Materials and mode of Operation. 1st The bobbins are filled with yarn and placed in the body of the machine. 2nd The ribs or wood which forms a component part of the Reed, Headville, or Heddles are introduced to the barrel of the flier in the machine and passed through both flier and bobbin which lays in the flier and is confined to one end of the carriage and the other end to the other and tightly drawn by a screw in order to stand the operation of the machine after which the yarn is taken from the Bobbin passed over the proper conductor attached to the springs or body of the flier down through the passage in the foot of the flier to the ribs to which it is made fast.

3rd The wire or spiles are introduced. 4th the main shaft is put in motion the first cog of which immediately advances the spile is introduced and places it in its proper station or position for cutting.

5th The beam or swage at the same instant engages the lever which directs the flier forward into the spile and instantly forces it to its final place. 6th The second wheel then comes in contact with the winding machinery which gives a circular motion to the flier at the same instant the flier commences this revolution the carriage commences graduation and forces the ribs on their proper degree by the time the fliers have completed their revolution, the flier which is turning

stand in a fixed position while the ribs are gradually passing through them. At the same instant the pins complete their revolution they are drawn back by the power of a spring which places them in a position to give reception to a succeeding fillet. Each part of this machine performing the several motions of feeding, cutting, gauging or gradually and adjusting the said rib. Each of the said parts may be moved by either of the mechanical powers in different forms and regulated by different agents and the whole collectively or singly, may be put in motion and worked by any power whatever that is capable of turning a wheel and going over a crank. Since the fillet is applicable to any shape of winding or covering with thread, yarn or any other material that can be used in that capacity, any substance either of wood, wire, bone, cordage or any other material of length and equal size that can bear the operation of the machinery or fillet when passing through its body in regular progression with the revolution of the said wheel.
